GOAL POST

James Trimble, R.R. 1-Hudson, Quebec, Quebec, Canada,
and Joel Rottman, 113 Finchley Road, Hampstead,
Quebec, Canada

Filed Dec. 20, 1966, Ser. No. 5,131

Term of patent 14 years

(Cl. D34—5)

FIGURE 1 is a perspective view of the goal post of our new design as seen from the front and somewhat to one side of the middle thereof; and

FIGURE 2 is a side elevation view of the goal post of FIGURE 1.

The goal post of our design is principally characterized by a single, generally cylindrically curved standard including a lower portion which is substantially straight so as to extend vertically upwardly from a supporting surface, and merges smoothly at its upper extent with an upper portion which extends curvilinearly upwardly and forwardly in an arc approximating the configuration of a quadrant of an ellipse; the standard upper portion, at its upper, forward extent supports at the center thereof, a horizontally disposed, generally cylindrical crossbar, said

crossbar having a vertically upwardly extending generally cylindrical upright thereon at each of the two opposite ends thereof.

We claim:

The ornamental design for a goal post, as shown and described.
